FOREIGN PATENT DOCUMENTS

FR 2733013 10/1996

Primary Examiner — Cynthia Underwood(74) *Attorney, Agent, or Firm* — Polson Intellectual Property Law, PC; Margaret Polson(57) **CLAIM**

The ornamental design for a carabiner with zip tie, as shown and described.

DESCRIPTION

FIG. 1 is a top plan view of a carabiner with a zip tie, the gate being in broken lines is for illustrative purposes only and forms no part of the claimed design.

FIG. 2 is a bottom plan view of FIG. 1.

FIG. 3 is a rear side elevation view of FIG. 1.

FIG. 4 is a front side elevation view of FIG. 1.

FIG. 5 is a left side elevation view of FIG. 1.

FIG. 6 is a right side elevation view of FIG. 1; and,

FIG. 7 is a second embodiment of FIG. 1 showing a top isometric view, the portion between the symbolic break in length forming no part of the claimed design.
